FLUOROCARBON-AZOMETHINES

Wilbur H. Pearson, White Bear Township, Ramsey County, and Lyle J. Hals, St. Paul, Minn., assignors to Minnesota Mining & Manufacturing Company, St. Paul, Minn., a corporation of Delaware

No Drawing. Application January 28, 1950,
Serial No. 141,164

4 Claims. (Cl. 260—566)

1

This invention relates to novel chemical compounds and to methods of producing the same. More particularly it refers to carbon-fluorine-nitrogen compounds, and especially compounds of carbon, fluorine and nitrogen which include the structure

We have found that compounds of the type just named, especially those having the formula $\text{C}_n\text{F}_{2n+1}\text{N}$, in which n is a whole number of 2 or higher, are of considerable value. For example they may be employed as intermediates in the production of further chemical compounds, such as fluorocarbon acids, e. g. CF_3COOH , $\text{C}_2\text{F}_5\text{COOH}$ and other $\text{C}_n\text{F}_{2n+1}\text{COOH}$ acids, where n is any integer, and secondary amines, e. g. $(\text{C}_2\text{F}_5)_2\text{NH}$, having the general formula $(\text{C}_n\text{F}_{2n+1})_2\text{NH}$. Our carbon-fluorine-nitrogen unsaturates also provide interesting and useful source materials in the production of polymers including carbon, fluorine and nitrogen.

Certain compounds having carbon, fluorine and nitrogen joined together in the same molecule have been known prior to this invention. For example, fluorinated tertiary amines are disclosed in the co-pending application of Kauck and Simons Serial No. 29,955, filed May 28, 1948, now abandoned in favor of continuing application Serial No. 161,717, filed May 12, 1951. An example of such a tertiary amine is perfluorotriethyl amine,

Other examples of carbon-fluorine-nitrogen compounds are disclosed in U. S. patents of Joseph H. Simons Nos. 2,490,098 and 2,490,099, both granted December 6, 1949. Additionally certain other carbon-fluorine-nitrogen compounds have been known in the prior art, but, to the best of our knowledge, none of the type herein described and claimed. Further, some compositions have been referred to as containing compounds of carbon, fluorine and nitrogen, but such compounds are so different from the compounds of this invention and so unstable that, upon reaction with ammonia, nitrogen is liberated as a gas. $\text{CF}_3\text{CH}_2\text{NH}_2$ and CF_3CONH_2 are examples

2

of previously known compounds containing carbon, fluorine and nitrogen, plus one or more other elements.

It will be seen that the carbon-fluorine-nitrogen compounds of our invention, described and claimed herein, are to be distinguished from all the prior known compounds just mentioned. Also, as will presently be more fully illustrated, the compounds above mentioned, disclosed in the Kauck and Simons application Serial No. 29,955, illustrate tertiary fluorocarbon amines of the type contemplated by us for use as starting materials in making our $\text{C}_n\text{F}_{2n+1}\text{N}$ unsaturated compounds, in which n is a whole number, either 2 or more. A group of these compounds in which we are particularly interested are those in which n is an integer from 2 to 20.

Our carbon-fluorine-nitrogen compounds in general include the following structure

where free valences shown are joined to other carbon or fluorine atoms. It will be seen that compounds of such structure include, for example, compounds having the following empirical formulae $\text{C}_3\text{F}_7\text{N}$, $\text{C}_4\text{F}_9\text{N}$, $\text{C}_5\text{F}_{11}\text{N}$, and the like.

In addition to yielding novel compounds of the type just described and illustrated, the methods or processes herein set forth and illustrated also yield fluorocarbon olefins, having the general formula C_nF_{2n} , of which

and

are examples.

We have found that we can produce our aliphatic carbon-fluorine-nitrogen compounds from tertiary fluorocarbon amines by (a) heat decomposition or (b) decomposition at elevated temperatures in the presence of a catalyst. In other words we have discovered that we may produce our compounds from the tertiary fluorocarbon amines by pyrolytic or catalytic conversion of the latter, as hereinafter illustrated. The fol-

lowing equations illustrate the production of our novel compounds:

The particular reaction compounds which we obtain, as is illustrated hereinafter, depend upon the reaction conditions, including the nature of the catalyst, if any, as well as upon the starting materials. For example, depending upon the nature of the catalyst employed (where one is employed), we either produce C_4F_9N or $C_6F_{13}N$, where $(CF_3CF_2CF_2)_3N$ is the starting material.

Both the C_4F_9N and the $C_6F_{13}N$ are aliphatic compounds and involve the structure

referred to above.

In the equations just illustrated above it will be understood that the Δ symbolizes heat decomposition, which may, for example, be carried out at temperatures of the order of 600 to 800° C. The reference to catalyst in connection with the equation last shown above symbolizes a catalytic decomposition reaction, also carried out at elevated temperatures although, because of the catalyst, the temperature may be lower than in the straight pyrolytic reaction. Also, depending upon the nature of the catalyst used, the results of the reaction may be modified and the reaction products may be caused to differ in molecular weight and structure.

Having described the broad outlines of our invention and illustrated it in certain respects, we will now point out, by examples, just how our novel process may be carried out and how our new compounds may advantageously be produced.

First we will describe the equipment and general conditions employed by us in the thermal decomposition of tertiary fluorocarbon amines to yield our desired products.

Equipment and general procedure

A 16 inch section of graphite tubing of $\frac{3}{4}$ inch inside diameter, within a close-fitting iron pipe which served as a protective support, was heated by us over a 12 inch section in an electric furnace. The temperature was measured by means of a Chromel-Alumel thermocouple placed between the iron pipe and the lining of the furnace. Liquid fluorocarbon was introduced into the heated chamber by allowing it to drop at a steady rate from a separatory funnel into a section of the inner tube which was heated sufficiently to vaporize the liquid. The vapors were swept into and out of the reaction tube through close-fitting steel adapters with a stream of nitrogen gas.

The exit gas was condensed in a series of traps cooled successively by ice, Dry Ice-acetone, and liquid air. The condensate was then passed over sodium fluoride at 100° C. to free it of traces of HF. No other chemical treatment was given the reaction products before isolation and purification.

The product boiling below room temperature was fractionated through a vacuum jacketed column packed with $\frac{1}{8}$ inch single turn stainless steel helices. The product boiling above room temperature was fractionated through a glass helix packed column with a head cooled by ice

water. Compounds were identified by their physical properties and other characteristics.

Employing the foregoing equipment and general procedure, a number of specific reactions were carried out by us, of which the following are illustrative

Example 1

154 grams of tris(pentafluoroethyl) amine, i. e. $(C_2F_5)_3N$, was passed through the usual graphite tube at a flow rate of approximately .05 mol per hour, with an equi-molar quantity of nitrogen. The reaction tube was kept at 745° C., at which temperature about $\frac{2}{3}$ of the starting material was decomposed.

The principal products of reaction were (a) C_3F_7N , i. e. $CF_3CF_2-N=CF_2$, (b) C_3F_8 , i. e. $CF_3CF=CF_2$ and (c) C_2F_4 , i. e. $CF_2=CF_2$.

However the reaction products also included, in lesser quantity, the saturated compounds C_2F_6 and C_3F_8 . Also, as above indicated, about $\frac{1}{3}$ of the starting material, $(C_2F_5)_3N$, was left undecomposed.

The foregoing ingredients were separated by fractional distillation and identified. For example, the C_3F_7N was identified as boiling within the range of -18 to -13° C. (about 13.2° C.) and having a molecular weight within the range of 180-184. The weight of the C_3F_7N fraction was 15.0 grams.

The C_3F_7N fraction was further identified by infrared analysis; its infrared spectrum exhibits a strong band at 1770 cm^{-1} , which is characteristic of unsaturation. However the compound did not absorb bromine at room temperature, which indicates that the unsaturation is not of the carbon-to-carbon ($>C=CF_2$) type.

Upon treatment of the carbon-fluorine-nitrogen fraction, i. e., the CFN fraction, with an aqueous alkali in a closed, evacuated system, a vigorous reaction took place, with evolution of a gas, which latter dissolved in the solution when an excess of alkali was added. The solution, upon analysis, was found to contain equi-molar quantities of NH_3 , CO_2 and CF_3COOH , i. e. trifluoroacetic acid. The trifluoroacetic acid was definitely identified by its boiling point (approximately 72° C.) and infrared spectrum.

The C_3F_7N compound apparently hydrolyzed according to the following reaction:

The formation of the trifluoroacetic acid, CF_3COOH , from the C_3F_7N compound lends still further evidence that the C_3F_7N compound contains the structure

60 as a part of its entire molecular structure

The characteristic of our compounds which contain the structure

65 by which upon hydrolysis they form trifluoroacetic acid, CF_3COOH , and/or higher fluorocarbon acids, is one of their unique and valuable characteristics.

Example 2

70 275 grams of tris(heptafluoropropyl) amine, i. e. $(C_3F_7)_3N$, was passed through the previously

described graphite tube, at a flow rate of .05 mols per hour, with an equi-molar quantity of nitrogen. The reaction tube was kept at 660-670° C. The following compounds were obtained (upon separation of the reaction products by distillation):

	Moles of Product per 100 Moles of Starting Material Decomposed
CF ₄	2
C ₂ F ₄	4
C ₂ F ₆	4
C ₃ F ₈	25
C ₃ F ₉	19
C ₄ F ₁₀	24
C ₄ F ₁₂	1
C ₄ F ₉ N	73
Higher boiling fractions	35

From the foregoing it will be seen that, for each mol of starting material, i. e. (C₃F₇)₃N, decomposed, 0.73 mol of C₄F₉N, i. e.

was produced. Said compound had a boiling point of 12.3 to 12.5° C. This compound was also identified by tests as generally described in Example 1. Also, upon hydrolysis, with an aqueous base, it was found to yield pentafluoropropionic acid, i. e. CF₃CF₂COOH.

Example 3

466 grams of tris(nonafluorobutyl) amine, i. e. (C₄F₉)₃N, was passed through the previously described graphite tube at a flow rate of .04 mol per hour. The reaction tube was kept at a temperature of 645-650° C. The following compounds were obtained, upon separation of the reaction products by distillation.

	Moles of Product per 100 Moles of Starting Material Decomposed
Low boiling C ₁ and C ₂ compounds	19
C ₃ F ₈	19
C ₃ F ₉	34
C ₄ F ₁₀	17
C ₄ F ₉	14
C ₅ F ₁₂	35
C ₅ F ₁₁ N	77
Higher boiling fractions	22

For each mol of the starting material, i. e. (C₄F₉)₃N, decomposed, it will be seen that 0.77 mol. of C₅F₁₁N, i. e. CF₃(CF₂)₃N=CF₂, boiling at 39.0° C., was produced. This compound (also identified by tests as above described) was hydrolyzed in an aqueous alkali to give a 93% yield of C₅F₇COOH, i. e. heptafluorobutyric acid.

Example 4

303 grams of (C₃F₇)₃N was passed through the previously described graphite tube, but, as distinguished from the foregoing examples, this time the tube was packed with aluminum fluoride pellets (catalyst). The tube was kept at a temperature of 660-665° C. and the flow rate was .05 mols of (C₃F₇)₃N per hour, and an equi-molar quantity of nitrogen was used.

The following compounds were obtained, upon separation of the reaction products by distillation:

separation of the reaction products by distillation:

	Moles of Product per 100 Moles of Starting Material Decomposed
CF ₄	1
C ₂ F ₄	1
C ₂ F ₆	2
C ₃ F ₈	13
C ₃ F ₉	13
C ₄ F ₁₀	33
C ₄ F ₈	1
C ₄ F ₉ N	100
C ₄ F ₁₂	30
Higher boiling fractions	23

For each mol of the (C₃F₇)₃N starting material, it will be seen that the reaction yielded 1 mol of C₄F₉N, i. e. CF₃CF₂CF₂-N=CF₂, boiling at 12.3 to 12.5° C. That is, this gave a 100% yield of C₄F₉N on the basis of the starting material decomposed.

As compared with Example 2, which lacked the catalyst here employed, the present example shows a decrease in C₁ and C₂ fluorocarbons and an increase in C₄, C₅ and C₆ fluorocarbons.

Tests, as above described, were employed in identifying the CF₃CF₂CF₂-N=CF₂, i. e. the C₄F₉N, as well as other compounds above listed.

Example 5

315 grams of (C₃F₇)₃N was passed through the previously described graphite tube, but in this case packed with dry sodium fluoride pellets. The tube was maintained at a temperature of 660-665° C. The flow rate and other conditions and procedure were as described in Example 4.

The following compounds were obtained:

	Moles of Product per 100 Moles of Starting Material Decomposed
CF ₄	Trace
C ₂ F ₄	1
C ₂ F ₆	3
C ₃ F ₈	24
C ₃ F ₉	13
C ₄ F ₁₀	39
C ₄ F ₈	3
C ₄ F ₉ N	82
Higher boiling compounds	47

For each mol of the (C₃F₇)₃N starting material it will be seen that the reaction yields 0.82 mol of C₄F₉N, i. e. CF₃CF₂CF₂-N=CF₂, boiling at 12.3 to 12.5° C. That is, this gave an 82% yield of C₄F₉N on the basis of the starting material decomposed.

It will be seen that the sodium fluoride catalyst of this example changes the distribution of products as compared with Example 2, although the change is not as marked as in the case of the aluminum fluoride packing.

Example 6

Completely fluorinated diethyl propyl tertiary amines, i. e. (C₂F₅)₂NC₃F₇, when treated under conditions as above illustrated, were found to yield (in addition to saturated and unsaturated fluorocarbons) a plurality of compounds each having the important structure

above referred to. Where (C₂F₅)₂NC₃F₇ is thus

decomposed, $\text{CF}_3\text{CF}_2\text{N}=\text{CF}_2$ (boiling at -13.2°C) and $\text{CF}_3\text{CF}_2\text{CF}_2\text{N}=\text{CF}_2$ (boiling at 12.3 to 12.5°C) were produced, each having the structure

With differences in the tertiary amine starting materials, corresponding differences in the carbon-fluorine-nitrogen products, containing the

structure, will result. For example, where a completely fluorinated dipropyl ethyl tertiary amine is employed as the starting material, the carbon-fluorine-nitrogen reaction products are also $\text{CF}_3\text{CF}_2\text{N}=\text{CF}_2$ and $\text{CF}_3\text{CF}_2\text{CF}_2\text{N}=\text{CF}_2$, but their relative proportions are the reverse of those where the completely fluorinated diethyl propyl tertiary amine is employed as the starting material, as just indicated above.

This will serve to illustrate further how the carbon-fluorine-nitrogen products vary with differences in the completely fluorinated tertiary amine starting material.

Example 7

628 grams of $(\text{C}_2\text{F}_5)_3\text{N}$, which was also used in Example 1 hereof, was passed through the previously described graphite tube, at a flow rate of 0.15 mol per hour, using nitrogen as a carrier. As distinguished from Example 1, in this case the graphite tube was packed with an aluminum fluoride-aluminum oxide catalyst, prepared by partially reacting alumina with hydrogen fluoride. The packed tube was maintained at 500 - 550°C .

In addition to saturated and unsaturated fluorocarbons, upon fractionation a compound of the formula $\text{C}_4\text{F}_9\text{N}$ was obtained, the same having the structural formula $\text{CF}_3\text{CF}_2\text{N}=\text{CFCF}_3$ and boiling at 13.0 to 13.5°C .

It will be seen that the carbon-fluorine-nitrogen reaction product in this case is different from that of Example 1, having a different molecular weight. Also, although the empirical formula, $\text{C}_4\text{F}_9\text{N}$, is the same as that of the carbon-fluorine-nitrogen reaction product of each of Examples 2, 4, 5 and 6, yet infrared analysis indicates the product of this example to be readily distinguishable from the corresponding products of the other examples. Furthermore, upon hydrolysis, two mols of perfluoro acid (trifluoroacetic acid) are obtained from one mol of the $\text{C}_4\text{F}_9\text{N}$ product compound of this example.

In addition to the evidence of the structure, $\text{CF}_3\text{CF}_2\text{N}=\text{CFCF}_3$, provided by the hydrolysis, we also found that bromine is not absorbed at room temperature, which indicates (see Example 1) that the unsaturation is not of the terminal carbon-to-carbon type.

The relatively low temperature employed in this example, coupled with the use of a catalyst, provides our explanation of the important difference in the $\text{C}_4\text{F}_9\text{N}$ product compound.

Example 8

Using the same apparatus and procedure as employed in Example 7, we employed, however, $(\text{C}_3\text{F}_7)_3\text{N}$ as the starting material.

In addition to saturated and unsaturated fluorocarbons, we obtained the compound $\text{C}_6\text{F}_{13}\text{N}$, boiling at 56.5 - 57.5°C . and having the structure $\text{CF}_3\text{CF}_2\text{CF}_2\text{N}=\text{CFCF}_2\text{CF}_3$.

This product compound was identified by tests previously described herein and, like the $\text{C}_4\text{F}_9\text{N}$ product compound of Example 7, upon hydrolysis yielded 2 mols of perfluoroacid (perfluoropropionic acid) per mol of the said $\text{C}_6\text{F}_{13}\text{N}$ compound.

It will also be noted that, as in Example 7, the structure of this $\text{C}_6\text{F}_{13}\text{N}$ compound is widely different from compounds shown in earlier examples, in that it has such a structure that upon hydrolysis two mols of perfluoro acid are produced for each mol of the $\text{C}_6\text{F}_{13}\text{N}$ compound, that is, for each mol of the product compound having the structure

In addition to the productions above described, in Examples 1-8, we also carried out several larger scale preparations, in which we successively produced several hundred grams of each of the following compounds:

Upon reaction of the $\text{C}_3\text{F}_7\text{N}$, as produced in Examples 1 and 6, with HF at a temperature of about 125°C ., the HF adds on, the H becoming bonded to the N (as shown by infrared analysis), thus yielding a perfluoro secondary amine, i. e. $\text{CF}_3\text{CF}_2\text{NHCF}_3$. This addition reaction further demonstrates that compounds of this type, made up of carbon, fluorine and nitrogen have a double bond joined to the N.

Hereinabove we have referred to various fluorocarbon tertiary amines as the starting materials for our reactions. These tertiary amines may be referred to generally as $(\text{R}_f)_3\text{N}$, where R_f stands for a perfluoro hydrocarbon group and each R_f group may be the same or different. Each R_f group contains a carbon atom joined to the nitrogen.

Also hereinabove we have disclosed various compounds of carbon, fluorine and nitrogen which contain the structure

where the free valences are satisfied by fluorine or by perfluoro hydrocarbon groups. It will be understood that compounds of this type, in addition to those specifically named, are also contemplated.

Other novel embodiments and variations in products and methods will readily occur to chemists skilled in this art, in the light of the description and examples herein contained. All such embodiments and variations, as well as those herein specifically set forth, are likewise comprehended within this specification.

What we claim is:

1. An organic compound having the empirical formula $\text{C}_n\text{F}_{2n+1}\text{N}$ and containing the structure

where n is an integer of at least 2.

2. An organic compound having the empirical formula $\text{C}_n\text{F}_{2n+1}\text{N}$ and containing the structure

75 n being an integer from 2 to 20.

3. A compound of carbon, fluorine and nitrogen having the structure $R_f-N=CF_2$, where R_f denotes a perfluoro alkyl radical.

4. A method of producing organic compounds having the empirical formula $C_nF_{2n+1}N$ and containing the structure

which comprises heating a perfluoro alkyl tertiary amine to an elevated temperature within the approximate range of 400° to 800° C., so that new products are produced having the empirical formula $C_nF_{2n+1}N$, and containing the structure

15

where n is an integer of at least 2, all of the fluorine of the molecule being bonded to carbon atoms, and separating the $C_nF_{2n+1}N$ compounds from the remainder of the reaction mixture.
